CONDENSER FOR REFRIGERATING SYSTEMS

Johann Heinrich Hermann Voss,
White Plains, N. Y.

Application March 22, 1932, Serial No. 600,418

10 Claims. (Cl. 257—35)

This invention relates to an improvement in condensers designed more particularly for the condensation of ammonia or other liquefiable gases used as heat carrying agents in refrigerating cycles.

The improved condenser is directed more particularly to a means for effecting a complete separation of the lubricating oil from the gaseous refrigerating agent in such a manner that the separation takes place within the condenser structure; a particular detail of the improvement residing in the provision of means whereby the oil separation occurs during that phase of the condensing process in which the so-called "super-heat" is taken out of the high pressure gas. This particular detail resides in the provision of means whereby the lubricating oil is trapped and separated, ready to be drawn off, before the partly cooled refrigerating agent reaches that part of the condenser structure in which it is finally liquefied.

A further object of the invention is the provision of means whereby the non-condensable gases present in the refrigerating cycle, are separated from the refrigerant and are trapped within the condenser structure in such a manner that they are confined to a space from which they may be easily withdrawn, but from which they cannot return to intermingle with the saturated gas or the gas in process of condensation in other parts of the condenser structure.

A still further object of the invention is the provision of means whereby the high pressure refrigerant is passed through intercommunicating yet independent ringspaces formed between concentric tubes and condensed by means of a thin stream of cooling water running downwardly by gravity over the tube surfaces opposite to the confining tube surfaces of the refrigerant.

These and other objects of my invention will become more fully known as the description proceeds, and will then be specifically defined in the appended claims.

The invention is illustrated in the accompanying drawings, in which:

Fig. 1 is a view in elevation, partly in section, showing the improved condenser.

Fig. 2 is a cross-section on line 2—2 of Figure 1.

Fig. 3 is a top view of Figure 1, partly broken away on the line 3—3 of Figure 1 the water cooling means being omitted.

Fig. 4 is a cross-section of a modified form of a condenser.

Fig. 5 is a top view of same.

Fig. 6 is a top view of another form of condenser.

Fig. 7 is an enlarged sectional detail view of the upper part of the condenser as shown in Figure 2.

Fig. 7a is a sectional detail view of the flush ferrule.

Fig. 8 is a top view of the spaced ferrule in the condenser, in Figure 7.

Fig. 9 is an elevation partly in section of another modified form of condenser.

Fig. 10 is a section on line 10—10 of Figure 9.

Fig. 11 is an end elevation of the complete condenser installation, showing a plurality of condenser units constructed according to my invention seen along line 11—11 of Figure 13.

Fig. 12 is a side elevation thereof seen along line 12—12 of Figure 13.

Fig. 13 is a plan view of a complete condenser installation showing a plurality of condenser units.

The condenser shown in Figures 1, 2, 3, 7, and 8, embodies two horizontal headers, the upper header 10 and the lower header 11. They are in communication through the intermediary of a plurality of vertical tubes 12.

These tubes are connected by welding to the lower surface of the upper header, as at 13, and to the top surface of the lower header, as at 14.

The ends of the tubes reach almost to the opposite side of the header and leave just space enough to allow a free passage of the entering hot gas or the leaving condensed liquid refrigerating agent. Within the tubes 12 are provided the inner tubes 15 so as to just allow a narrow ring-space 16 between tubes 12 and 15.

The tubes 15 extend clear through both headers and serve as cooling means for the hot gases passing through ring-space 16. The hot gas enters into the upper header at 17 and is cooled thereby by a water cooling arrangement generally designated as at 18 which will be described later on.

The hot gas is, therefore, cooled down to a point where it has given up all or the larger part of its super-heat. During this time the lubricating oil is deposited in the lower part of the upper header from where it can be withdrawn through the oil-drain pipe 19, while the partly cooled gas enters the ring-space 16, and is condensed to a liquid, falling down into the lower header 11 from which it can be discharged through pipe 20.

The non-condensable foul gases are discharged through a purge outlet pipe 21.

The separation of the oil in the upper header is very effective due to the great number of baffles of large surface which are formed in a most simple and inexpensive manner by means of the vertical

pipes 12 and 15, extending into or passing through the upper header.

In the improved condenser the purging of the non-condensable or so-called "foul" gases is provided for in the form of a foul gas trap with a purge outlet at or near the top of the lower horizontal header.

The foul gas is retained in the upper part of the lower header by means of the outer or single pipes extending downward into the lower header and forming a dome in which the foul gas finds itself trapped and cannot return to mix again with the gas coming from the upper header nor with the liquid falling downward into the lower header, being separated from the condensing surfaces of the vertical pipes and from the upper headers by the walls of the vertical pipes extending into the lower header.

In those cases where a condenser plant consists of more than one unit it is advisable to equalize the pressure in the different units by means of a comparatively small pipe line connecting the upper headers at or near their top; this equalizing line may conveniently be further connected to the "foul" gas purge line connecting the different units at or near the tops of the lower headers and finally these two pipe lines are interconnected at some point located above the liquid receiver as is well known in the art.

The water cooling means 18 on top of header 10 is built as follows:

A plurality of substantially V-shaped supporting members 22 are welded to the top of header 10 and carry the liquid receiving trough 23. Said trough has perforations 24 in its sides near the top and openings 25 in the bottom, so as to make it possible for the water to flush the upper header in the center as well as on its entire periphery. A splash-apron 26 is set over the top of trough 23 and has holes 27 to allow free passage of the water. The water supply means 28 is mounted above the water trough 23.

Water retaining and guiding ferrules 29 are inserted in the top of the inner tubes 15. The water overflowing from the trough 23 runs down on the walls of the trough 23 and apron 26, as shown at 15', Figure 7, and covers the entire outer surface of the condenser, and the outside surfaces of tubes 12 and the inside surfaces of tubes 15 where the same are exposed to the atmosphere.

Figure 4 shows a modified arrangement of the tubes mounted in the upper header 10. Instead of allowing space between the outer tubes 12 and the header 10 to let the gas pass into the ring-space between 12 and 15, tube 30 extends clear up into the top of header 10 and is sealed on its fastening point although it has slot 32 on the top for the passage of the gas.

Figure 5 shows an arrangement of a plurality of rows of vertical tubes arranged in staggered relation.

Figure 6 shows these vertical tubes in a single-row arrangement.

Water retaining and guiding ferrules 29 (shown in Fig. 8) may be inserted in the top of the inner tubes 15 and have wings 33 mounted thereon for directing some of the water into the inner tube 15.

Figure 7 shows a flush ferrule in which the water retaining and guiding ferrule 29a projects beyond and fits closely within the inner tube 15 and has wings 33a similar to the wings 33 in Figure 8.

Figures 9 and 10, show a modified arrangement

of a condenser using a single tube 42 as communication between upper header 40 and lower header 41.

The hot gas enters the upper header 40 through the inlet 43, where it is partly cooled while the lubricating oil is deposited and can be withdrawn through pipe 44.

The partly cooled gas enters into the tubes 42 where it is condensed and falls as liquid into the lower header 41. The condensed liquid is withdrawn through outlet 46, while the foul gases are purged through pipe 47. With this arrangement there is no inside-cooling arrangement for the gases provided while passing through tubes 42. The equalizing line 45 is provided at the top 15 of the upper header 40.

As shown in Figures 11, 12 and 13 the hot compressed ammonia gas coming from the compressor through the main discharge pipe 55 passes the oil separator 54 and enters the individual units 12 through the header 56 and is controlled by the valves 60. The liquid ammonia leaves the lower headers of the units 12 through the outlet valve 62 and flows into the liquid receiver 51 through the pipes 61.

The main water header 28 supplies through branches the cooling water into the troughs 23 from where it runs over the condenser units 12. The lower headers of each unit 12 of the battery are connected by the foul gas purge line 52 which connects with the liquid receiver 51 and is controlled by valve 53. The tops of the upper headers of units 12 are connected by the equalizing line 48, which is further connected by branch 50 with the foul gas purge line 52 and is controlled by valve 49. The foul gas purge line 52 is further connected by the pipe 57 to the foul gas purger which may be conveniently located in the engine room.

The bottoms of the upper headers of units 12 are connected by the oil drain line 58.

The operation of my device will be readily understood from the above description by simultaneous reference to the drawings, and it will be clear that the hot gas coming from the compressor upon entering the upper header is cooled to the point where it gives up all or the larger part of its superheat. During this time the lubricating oil is deposited in the lower part of the upper header from where it can readily be withdrawn through the oil drain pipe while the gas which is partly cooled will enter the ring-space between the outer and inner pipes or the circular space in the single pipe and will therein be condensed to a liquid falling down into the lower header from where it can be piped into a liquid receiver.

The non-condensable gases are effectively trapped in the upper part of the lower header, they are prevented from returning to intermingle with the condensing gas in the ring-spaces and are easily purged at the top of the lower header.

The cooling water runs downwardly by gravity from the trough and covers the entire condenser structure where it is exposed to the atmosphere on the outside of the upper header, on the outside of the outer vertical tubes, on the inside of the inner vertical tubes and on the outside of the lower header.

The efficacious cooling action of the rapidly descending water surrounding the thin film of the high pressure refrigerant within the vertical tubes is effectively maintained at a high rate of heat transmission by means of the effectual elim- 75

ination of the lubricating oil and the non-condensable gases from the area of condensation.

It will be understood that I have described and shown the preferred forms of my invention only as examples of the many possible ways to practically construct my invention, and that I may make such changes in the general construction of its minor details as come within the scope of the appended claims without departure from the spirit of my invention and the principles involved.

Having thus described my invention, what I claim as new and desire to secure by Letters Patent is:

1. A condenser for refrigerating systems comprising an upper and a lower header, a plurality of vertical double, concentrically arranged pipes establishing communication between said headers and supported thereby, the ends of the outside pipes extending close to the opposite walls of the headers with space enough to allow a free passage of the entering hot gas freed of its superheat the gas being condensed in the space between the concentric pipes and the condensed liquid refrigerating agent falling into the lower header, said pipes bunched to form a compact single piece condenser.

2. In a condenser for refrigerating systems, an upper header for depriving the hot gas from a compressor of its superheat, a lower header, a foul gas trap with a purge outlet, near the top of said lower header, a dome formed in the upper part of said header for retaining the foul gas to prevent its mixing with the gas coming from the upper header or the liquid from said upper header.

3. In a condenser for refrigerating systems, a plurality of concentrical tubes having independent yet intercommunicating ring spaces formed therebetween, and means for passing a high pressure refrigerant through said spaces to be condensed therein by means of a thin stream of cooling water running downwardly by gravity over the tube surface opposite to the confining tube surfaces for the refrigerant, and water supply means.

4. In a condenser for refrigerating systems upper and lower headers, double walled connecting pipes between said headers, a sheet iron ferrule inserted into the top of the inner of said double pipes, and side flaps or wings on said ferrule for catching a certain amount of the cooling water to guide it into the ringspace between said ferrule and the inner surface of said double pipes causing the water to flow downward in the inner pipe and to cool the gas to condensation.

5. In a condenser for refrigerating systems, upper and lower headers, double walled connecting

pipes between said headers, a ferrule and wings on said ferrule extending over a certain width of the upper header.

6. In a condenser for refrigerating systems, upper and lower headers, concentric pipes connecting the upper and lower headers extending through the upper wall partition of the upper header, the outer of said pipes partly slotted in its upper part to provide a gas inlet to the ring-space between the two concentric pipes.

7. In a condenser for refrigerating systems comprising a plurality of single pipes supported by headers, an upper water cooled header for depriving the hot gas from the compressor of its super-heat, a lubricating oil trap with a purge outlet in the lower part of said header, a lower water cooled header, a foul gas trap with a purge outlet, near the top of said lower header, a dome formed in the upper part of said header for retaining the foul gas to prevent its mixing with the gas coming from the upper header or the liquid from said upper header.

8. In a condenser for refrigerating systems comprising a plurality of single pipes supported by headers, an upper water cooled header for depriving the hot gas from the compressor of its super-heat, a lubricating oil trap with a purge outlet in the lower part of said header, a plurality of baffles of large surface in form of pipes extending into the upper header for the separation of the oil in the same, a lower water cooled header, a foul gas trap with a purge outlet, near the top of said lower header, a dome formed in the upper part of said header for retaining the foul gas to prevent its mixing with the gas coming from the upper header or the liquid from said upper header.

9. In a condenser for refrigerating systems built up from units, a plurality of upper headers and a plurality of lower headers, vertical pipes extending from the upper headers into the lower headers, a comparatively small pipe line connecting the upper headers near their top for equalizing the pressure in the different units, a foul gas purge line connecting the units, a liquid receiver with which said foul gas purge line connects, a connection between the equalizing line and the foul gas purge line of the various units near the top of the lower headers, and means of interconnection between the two pipe lines above the liquid receiver.

10. In a condenser for refrigerating systems as claimed in claim 9, an oil drain line connecting the bottoms of the upper headers of the condenser units for draining the oil directly from said units.

JOHANN HEINRICH HERMANN VOSS.
